(57) **CLAIM**

The ornamental design for filter element having an inlet grid, as shown and described.

DESCRIPTION

FIG. 1 is an end view of a filter element having an inlet grid, embodying our new design, being for illustrative purposes only and forming no part of the claimed design;
FIG. 2 is a side elevational view of the embodiment depicted in FIG. 1, the portions shown in broken lines being for illustrative purposes only and forming no part of the design claimed; the opposite side elevational view being a mirror-image thereof;

FIG. 3 is a top plan view of the embodiment depicted in FIG. 1, the portions shown in broken lines forming no part of the design sought to be patented;

FIG. 4 is a bottom plan view of the embodiment depicted in FIG. 1, the portions shown in broken lines forming no part of the design sought to be patented; and,

FIG. 5 is an end view opposite of the end view of FIG. 1, the portions shown in broken lines forming no part of the design sought to be patented.
